UNITED STATES PATENT OFFICE.

JOHN ALDERSLEY, OF NEW YORK, ASSIGNOR OF ONE-HALF TO WILLIAM N. MILSTED, OF BROOKLYN, N. Y.

GAS-STOVE.

SPECIFICATION forming part of Letters Patent No. 293,698, dated February 19, 1884.

Application filed July 31, 1883. (No model.)

To all whom it may concern:

Be it known that I, JOHN ALDERSLEY, of the city and county of New York, in the State of New York, have invented a new and useful Improvement in Gas-Stoves, of which the following is a specification.

My invention relates more particularly to a gas-stove which has an upper baking-chamber and a lower roasting or cooking chamber, with a main burner arranged horizontally between them.

The invention consists in the combination, with an upper baking-oven and a lower roasting or cooking chamber, of a gas-burner arranged between them, and removable non-conducting shields or partitions adapted to be placed in said oven and chamber above and below the burner. When the oven is to be used, a shield or partition is to be placed immediately below the burner in the roasting-chamber, to keep the heat from the said chamber, and when said chamber is to be used for roasting or other purposes a shield or partition is placed in the bottom of the oven, to prevent the radiation of heat upward.

The invention also consists in the combination, in a stove, with a chamber containing a burner and a superposed oven surrounded by heating flues or spaces, of a lateral extension furnished with a pot hole or holes and a damper for directing the heat from said burner through said lateral extension or through the flues or spaces around said oven.

The invention also consists in the combination, with the aforesaid burner and an oven arranged above the same and surrounded by heating-spaces, of a lateral extension provided with one or more pot-holes and dampers, whereby the heat may be caused to pass directly upward around the oven, or first through the lateral extension and then up and around the oven.

The invention also consists in the combination, with a chamber containing the aforesaid burner, which I may term the "main burner," of a lateral extension provided with one or more pot-holes, and through which the heat may be passed from the main burner when the full heat from said burner is not required for cooking above or below it, and an auxiliary burner arranged in the extension for use when

the full heat from the main burner is required elsewhere, or when it is not desired to use the main burner.

The invention also consists in the combination, with the aforesaid auxiliary burner, of an air damper or register in the bottom of the extension, which may be opened when it is desired to use the auxiliary burner, but which is closed when the extension is to receive heat from the main burner. The stove may have two or more of the above-described lateral extensions, and each extension may have as many auxiliary burners as it has pot-holes.

The invention also consists in novel features in the construction of the lateral extensions aforesaid, some of which features are especially desirable when an extension has two auxiliary burners, for the purpose of hastening the escape of the waste products of combustion from one burner, which only is then in use.

The invention also consists in other features of construction and combinations of parts hereinafter described and claimed.

In the accompanying drawings, Figure 1 is a vertical section of a stove embodying my invention. Fig. 2 is a sectional view, upon a larger scale, of one of the auxiliary burners. Fig. 3 is a sectional view of one of the non-conducting removable shields or partitions. Fig. 4 is a vertical section on the dotted line *x x*, Fig. 1, the main burner alone being shown in exterior elevation. Fig. 5 is a view of one of the lateral extensions, looking from the side usually joined to the stove. Fig. 6 is a perspective view of the lateral extension detached from the stove, and with the top removed. Fig. 7 is a perspective view, showing an arrangement of dampers hereinafter described. Fig. 8 is a horizontal section on the dotted line *y y*, Fig. 1, a portion of the top of the right-hand lateral extensions being broken away. Fig. 9 is a front elevation, on a smaller scale, of the stove. Fig. 10 is a plan on the same scale as Fig. 9, illustrating a modification of my invention; and Fig. 11 is a sectional view of a cover hereinafter described.

Similar letters of reference designate corresponding parts in all the figures.

The several portions of the stove-casing may be constructed of cast or sheet metal, as may

be most suitable. In the main portion of the stove are constructed a lower chamber, A, for roasting or cooking, and an upper baking-oven, B, and between them is arranged a horizontal gas-burner, C, of ordinary construction.

D designates the main gas-pipe, and D' designates branch pipes leading to the burner C, and of which two are shown in Fig. 8. In 10 each branch pipe D' is an air-inlet, a, through which air enters to mix with the gas. In lieu of one large burner, C, I may use two or more smaller burners arranged side by side, and capable of being used separately or together.

15 The chamber A and oven B are provided on their inner sides with ledges or supports b, whereon the shelves or racks may be placed. When it is desired to get as strong heat as possible in either the oven B or chamber A, it is of course advantageous to prevent the 20 radiation of heat into the chamber A or oven B; and to this end I employ removable partitions or shields A' B', which are adapted to be placed on the ledges b, as shown in the case

25 of the shield A', Fig. 1. These shields may be constructed of two sheets of iron with a layer of asbestos between them. The shield A' prevents a large proportion of the heat from being directed down into the chamber A and 30 radiated outward from the walls thereof, and so produces a more intense heat in the oven B.

The shield B' for the oven B is shown in Fig. 3; and when it is desired to roast or do other cooking in the chamber A, I remove the 35 shield A' therefrom and put the shield B' at the bottom of the oven B, as shown by dotted lines in Fig. 1.

In the bottom c of the oven B, I form a pot-hole, d, and when the oven is not desired to 40 be used I may place a kettle, E, or any vessel, on the hole d, and heat it very rapidly.

On the two sides and back of the oven B are heating-spaces e, and the hot products of combustion pass upward around the oven B, thence 45 under a plate, e', (shown in Fig. 4,) which plate causes them to pass over the top of the oven, and thence over said plate to the outlet-pipe e'. (Also shown in Fig. 4.) At the front edge of the plate e' the edge e' is turned upward, so 50 as to prevent the heavy products of combustion which may settle on the plate e' from returning below said plate, and to carry away said heavy products the outlet e' is made slightly lower than the plate e', as shown in

55 Fig. 4.

At one or each side of the main portion of the stove I attach a lateral extension, F, wherein are one or more pot-holes, d'. As shown in Figs. 1 and 8, there are extensions on the 60 right and left sides of the stove, and I may, if desired, arrange a third extension at the back, as shown by dotted lines in Fig. 10. As shown in Figs. 1 and 8, each extension has two pot-holes, d'; but one or each extension 65 may have four pot-holes, d', as shown in the case of the right-hand extension in Fig. 10. In each extension F there is a lateral parti-

tion, f, which extends nearly but not quite to the outer side thereof, leaving a passage or aperture, f', around its outer edge, for the 70 passage of the products of combustion above said partition when they return inward. The space below the partition is divided by an upright partition, f'', between the pot-holes, and, as best shown in Fig. 1, the pot-holes are in 75 the partition f, as well as in the top of the extension, and the well of the kettle E' or boiler E'' projects downward through the partition f. The extension F may be supported by brackets F', and where a long extension is 80 used, as shown at the right hand of Figs. 9 and 10, I may support the outer end of the extension by a leg, F'', as shown in Fig. 9. The space below the extension may then be 85 enclosed and fitted with shelves f', (shown dotted in Fig. 9,) so as to serve as a hot closet. A second stove may be placed by the side of the first, with the extensions of the two meeting, as shown dotted in Fig. 9, and the space below the meeting extensions may be fitted up 90 to serve as a hot closet.

At the junction of each extension F with the main portion of the stove are dampers g, g', attached to a common shaft or spindle, g'', which projects through the front of the stove, 95 and is provided with a handle, g', for turning it. The dampers g control the passage upward to the side heating spaces or flues, e, of the oven, and the dampers g' control the passage into the extension F below the partition f. 100 When the heat from the burner C is not all otherwise required, I turn the dampers g, g' into the positions shown at the left hand of Fig. 1, thus opening the passage into the extension F, and closing by the damper g the passage directly upward into the flue or space e. The hot air and products of combustion will then pass through the extension under the partition f, through the aperture f', and back 105 over the partition f, to the flue e, and thence 110 upward. The hot products of combustion come in contact with the bottom of the kettle E' in their passage outward, and impinge around the side of the kettle-well in their passage inward. The heavier products of combustion will settle on the bottom of the extension, and I provide checks or guards h, (shown 115 in Figs. 1 and 4,) which form pockets to catch and retain these heavy products of combustion, and prevent them from getting round 120 the burner C and impeding combustion.

When all the heat from the burner C is required elsewhere, the dampers g, g' are turned into the positions shown at the right of Fig. 1, to close the passage into the extension and 125 open the passage directly into the heating flue or space e. To the end that the extension may be used, even when all the heat from the main burner C is required elsewhere, I arrange an auxiliary burner, C', below each 130 extension pot-hole d', and these auxiliary burners are supplied with gas by means of branch pipes D' from the main pipe D. In each branch pipe D' is an air-inlet, a. The aux-

iliary burners are of well-known form, and consist of a hollow annular ring, *i*, provided with perforations, as best shown in Fig. 2. In the burners *C'* (shown in the left-hand extension in Figs. 1 and 8) the branch pipes *D'* deliver the gas directly into the hollow ring *i*; but in the burners shown in the right-hand extension in said figures, and in Fig. 2, the gas is delivered by the pipes *D'* at the center, and passes through a passage, *i'*, to the ring *i* of the burner. The auxiliary burners *C* may be cast complete in themselves; but I prefer to form the rings or shells *i* without bottoms, and attach them to the bottoms of the extensions, the said bottoms of the extensions forming the bottoms of the burners, as shown in Fig. 2.

In order to supply the necessary amount of air for the combustion in the burners *C'*, I form holes or apertures *i*² on the inside of the two rings *i*, and perforations *i*³ on the outer side of the said rings. The passage of air through the openings *i*² *i*³ is controlled by register plates or valves *G*, which are placed on the under sides of the extensions, and are adapted to be turned so as to allow air to enter when the auxiliary burners *C'* are used, and so as to cut off the entrance of air when the extensions are heated by the main burner *C*. At the back of the stove and on opposite sides of the oven are escape-flues *j* for the products of combustion from the auxiliary burners, and each flue is controlled by a damper, *j'*. When the auxiliary burner *C'* which is nearest the front of the stove is in operation, the other pot-hole *d'* in that extension is closed by a cover shaped like the well of a kettle, and adapted to extend through the hole in the partition *f*. Such a cover is shown in Fig. 11. The waste products of combustion from the burner in use pass upward through the aperture *f'*, and in order to prevent them from falling through the aperture *f'* on the opposite side of the partition *f*², I arrange a hinged damper plate or guard, *k*, (shown in Fig. 8,) which, by means of a rod and handle, *k'*, may be pushed over against the cover in the back pot-hole, thus closing the passage to the aperture *f'* of the burner, which is not lighted, and directing the products of combustion from the other burner toward the flue *j*.

At the back of the oven *B* is a hinged damper, *l*, which, by means of a handle, *l'*, (shown in Figs. 4 and 8,) may be opened or closed. In lieu of a hinged damper at the back, I may employ a fixed plate provided with perforations *l*². (Shown dotted in Fig. 8.)

As shown in Figs. 1, 4, and 8, the dampers *l* and *g* are all operated separately; but in order to avoid going round to the back of the stove when the back damper is to be opened, I may provide the shaft *g*² of one of the pairs of dampers *g* *g'* with an arm, *g*⁴, which extends under the back damper, *l*, as shown in Fig. 7, and when the said shaft is turned to shift the dampers *g* *g'* carried by it, it will also raise the damper *l* by means of the arm *g*⁴.

The chamber *A* and oven *B* are provided at

the front with the usual doors, *A*² *B*², to afford access to them.

What I claim as my invention, and desire to secure by Letters Patent, is—

1. The combination, with an upper baking-oven and a lower roasting or cooking chamber, of a gas-burner arranged between the two, and non-conducting shields or partitions removable fitted to the oven and chamber, substantially as and for the purpose described. 75

2. In a gas-stove, the combination, with a chamber containing a burner and a superposed oven surrounded by heating flues or spaces, of a lateral extension furnished with one or more pot-holes, and a damper for directing the heat from the burner through said lateral extension, or through the flues or spaces around said oven, substantially as and for the purpose described. 85

3. In a gas-stove, the combination, with a burner and a superposed oven surrounded by heating flues or spaces, of a lateral extension provided with one or more pot-holes, and dampers whereby the heat may be caused to pass directly upward around the oven, or first through the lateral extension and then around the oven, substantially as herein described. 90

4. In a gas-stove, the combination of a chamber containing a main burner, a lateral extension provided with one or more pot-holes, a damper for directing the heat from the burner through said lateral extension, and one or more auxiliary burners arranged in the lateral extension, substantially as herein described. 95

5. In a gas-stove, the combination, with a chamber containing a main burner, and a lateral extension through which the heat from the main burner may be directed, of an auxiliary burner in said extension, and a draft plate or valve controlling the admission of air to the auxiliary burner, and adapted to be closed when the extension is heated by said main burner, substantially as herein described. 105

6. The combination of a chamber containing the main burner *C*, the lateral extension *F*, having the horizontal partition *f*, and a damper for directing the heat from the burner *C* under and then over the partition *f*, substantially as 110 described.

7. The combination of the oven *B* with its surrounding heating-space *e*, a burner, *C*, arranged in a chamber below the oven, the lateral extension *F*, with its partition *f*, and the dampers *g* *g'*, substantially as described. 115

8. The combination of the oven *B* with its surrounding heating-space *e*, a burner, *C*, arranged in a chamber below the oven, the lateral extension *F*, with its partition *f*, the dampers *g* *g'*, and the shaft *g*², to which both dampers are attached, substantially as described. 125

9. The combination of the chamber containing the main burner *C*, the lateral extension *F*, with the partition *f*, and having a pot hole or holes extending through said partition, and the damper *g*², substantially as described. 130

10. The combination of a chamber containing the main burner *C*, and the lateral extension

F, constructed with the horizontal partition f and the vertical partition f^2 , and having pot-holes on opposite sides of the partition f^2 , substantially as described.

5 11. The combination, with the lateral extension F, constructed with the horizontal partition f , the vertical partition f^2 , and two pot-holes, d' , of auxiliary burners C' on opposite sides of said partition f^2 , and the hinged guard or damper plate h , substantially as herein described.

12. The combination, with a chamber containing the main burner C, of the lateral extension F, and the checks or guards h , for confining the products of combustion, substantially as described.

13. The combination, with the oven B, having the heating-space e at the sides and back, of the burner C, the dampers g at the sides of the oven, the damper l at the back of the oven, and connections between one of the dampers

g and the damper l , whereby both said dampers can be opened by manipulating the damper g only, substantially as described.

14. The combination, with the baking-oven 25 B, the main burner C, and flues or heating-spaces e around the oven, and having a main outlet-flue at the top, of the lateral extensions F, containing auxiliary burners C', and an outlet-flue, j , leading upward from each extension to the main outlet-flue, and provided with a damper, j' , substantially as described.

15. The combination, with the extension F, of the auxiliary burners C', each consisting of a bottomless shell secured upon the bottom of the extension, the said bottom of the extension forming the bottom of the burner, substantially as described. JOHN ALDERSLEY.
